UNITED STATES PATENT OFFICE.

CHARLES E. VAN OSDOL, OF GREENSBURG, INDIANA, ASSIGNOR TO THEOPHILUS KING, TRUSTEE, OF BOSTON, MASSACHUSETTS.

ADJUSTABLE CASING FOR PNEUMATIC STACKERS.

No. 866,240.

Specification of Letters Patent.

Patented Sept. 17, 1907.

Application filed February 4, 1907. Serial No. 355,529.

To all whom it may concern:

Be it known that I, CHARLES E. VAN OSDOL, a citizen of the United States, residing at Greensburg, in the county of Decatur and State of Indiana, have invented 5 certain new and useful Improvements in Adjustable Casings for Pneumatic Stackers, of which the following is a specification.

The object of my invention is to produce a blast fan-member for pneumatic straw stackers, preferably entirely of metal, which may be readily adjustable in its 10 dimensions in order to fit any one of a number of different sizes or makes of threshing machines or other similar crop treating machines.

The accompanying drawings illustrate my invention. 15 Figure 1 is a side elevation of an embodiment of my invention; Fig. 2 an end elevation; Fig. 3 a section on line 3 3 of Fig. 2; Fig. 4 a section on line 4 4 of Fig. 1.

In the drawings 10 indicates side sills preferably formed of metal tubes, and each of said sills carries a 20 box 11 adapted to receive a shaft of a suitable blast fan to be mounted in the casing 12. The casing 12 is provided with a delivery spout 13 which, at its outer end, has a substantially vertical cylinder portion 14. Leading into the eye of the fan casing 12 is the usual inclined 25 hopper 15 which extends across the frame. The two sills 10—10 are connected at their outer ends by a transverse sill composed of a pair of members 16 and 17, one telescoped within the other and provided with fastening means 17' by which they may be held in any desired 30 position of adjustment. Secured to each sill 10 are two uprights 18—18 connected at their upper ends by a bar 19, said parts being conveniently of commercial angle iron. Secured to each pair of uprights 18 is a side plate 20 which extends between the sill 10 and the beam 19. 35 Secured to each beam 19 is a pair of uprights 21, to which is secured a plate 22 which is in the same plane as plate 20 and supplements said plate. Adjustably connected to each upright 21 by means of suitable bolts or other fasteners 23 is an upright 24 and the upper ends 40 of each pair of uprights 24 are connected by a horizontal beam 25. Secured to beams 25 is a vertical plate 26 which is provided at an intermediate point with a horizontal offset 27 so that its lower edge may overlap the upper edge of plate 22, the arrangement being such 45 that uprights 24 may be adjusted vertically upon uprights 23, while at the same time maintaining a continuous side wall composed of the overlapping plates 22 and 26. Each beam 25 carries a horizontal top plate

29 and the two top plates overlap at their inner edges so as to form a closed top for the casing. In order to 50 complete the structure I provide two transverse angle irons 30—30 which are secured at one end to one of the beams 25, and the two beams 31—31, which are secured to the other beam 25 and which overlap angle irons 30 at their inner ends, being attached thereto by bolts or 55 other suitable fastenings, as 32, in the manner shown, so that the two beams 25—25 may be separated or brought together by an adjustment of the overlapping angle irons 30 and 31.

The rear wall of the casing is formed by three pairs of 60 overlapping plates. A plate 40 is secured to one rear upright 18 while a plate 41 is secured to the other upright 18, the inner ends of the plates 40 and 41 overlapping, as shown. Secured to one rear upright 21 is a plate 42 and secured to the other rear upright 21 is a 65 plate 43, and these plates overlap each other at their inner edges. Secured to one rear upright 24 is a plate 44, the lower edge of which overlaps the upper edge of plate 42, and secured to the other rear upright 24 is a plate 45, the lower edge of which overlaps the upper 70 edge of plate 43, the inner edges of plates 44 and 45 overlapping, as shown. By this arrangement the casing may be increased both in height and in width while still maintaining continuous walls, the arrangement being such that, by proper adjustments of the parts, 75 the forward open end of the casing may be slipped over the rear end of any threshing machine, or other crop treating machine, and held in place by any desired means. The two uprights 24 are provided with brackets 50 which are connected by a suitable cross bar 51, 80 to which is attached the turn-table platform 52, the turn-table 53 of any pneumatic stacker being mounted thereon in any desired manner. In order to compensate for the vertical adjustment of the uprights 24, the platform 52, or the turn-table 53, carried a downwardly 85 projecting cylindrical sleeve 54, which sleeves downwardly over the portion 14 of the fan casing discharge spout, thus maintaining the connection between the fan casing and the pneumatic stacker, no matter what the adjustments of the parts may be. 90

I claim as my invention:

1. A pneumatic attachment for crop-treating machines comprising a plurality of overlapping metallic sheets, and a plurality of overlapping frame members connected by means permitting adjustment one upon the other to vary 95 the internal dimensions of the casing.
2. A pneumatic attachment for crop-treating machines

comprising a plurality of overlapping metallic sheets, and a plurality of overlapping frame members connected by means permitting adjustment one upon the other to vary the internal dimensions of the casing, and a fan housing.

- 5 3. A pneumatic attachment for crop-treating machines comprising a casing composed of a pair of overlapping lower sections one of which carries a fan housing, a pair of overlapping upper sections which also overlap the lower sections, and means for clamping the several sections
- 10 together in various positions of relative adjustment where-

by the internal cross dimensions of the casing may be varied.

In witness whereof, I, have hereunto set my hand and seal at Indianapolis, Indiana, this twenty-sixth day of January, A. D. one thousand nine hundred and seven.

CHARLES E. VAN OSDOL. [L. S.]

Witnesses:

ARTHUR M. HOOD,

THOMAS W. MCMEANS.
